(57) **CLAIM**

The ornamental design for a vehicle auxiliary light, as shown and described.

DESCRIPTION

FIG. 1 is a front perspective view showing a vehicle auxiliary light of the present invention;

FIG. 2 is a front view thereof;

FIG. 3 is a rear thereof;

FIG. 4 is a top view thereof;

FIG. 5 is a right side view thereof;

FIG. 6 is a left side view thereof; and,

FIG. 7 is a bottom view thereof.

In the drawings, the broken line showings are for the purpose of illustrating portions of the vehicle auxiliary light or environmental structure that form no part of the claimed design.
